BROILER

Irvin H. Raber, Los Angeles, Calif., assignor, by
mesne assignments, to Irwin Corporation, Los
Angeles, Calif.

Application October 23, 1936, Serial No. 107,141

10 Claims. (Cl. 126—41)

As the title indicates, the device of this invention relates to broilers, particular reference being had to the type of broiler used in hotels and restaurants, for the purpose of broiling 5 meats, etc. However, in addition to serving as broiler for meats, etc., it includes features that, insofar as I am aware, have never been used heretofore, i. e., the device serves also as a hot-plate for the purpose of preparing the so-called 10 short-order, also for the baking of pastries.

It has been a common experience heretofore, in broiling meats, that the operator of the broiler was very apt to either over do the meat or to broil it too rare, either condition being unsatisfactory to the epicure of well prepared foods.

It is therefore a prime object of the present invention to provide a broiler wherein the subject matter may be brought within variable degrees of heat, to the end that the heat of the 20 broiler may be more efficiently applied than heretofore.

A further object of the present invention is to provide a broiler that is simple in design, does not require expert attendance, and which produces superior results.

A further object of the invention consists in the novel and useful provision, formation, construction, association, and relative arrangement of parts, member and features, all as shown in certain embodiments in the accompanying drawings, generally described, and more particularly pointed out in the claims.

In the drawings of which there are four sheets:

Figure 1 is a front elevation of the device of this invention.

Figure 2 is a plan view of the same.

Figure 3 is a side elevation showing operating mechanism of the broiler.

Figure 4 is a side elevation taken on line 4—4, Fig. 1.

Figure 5 is a sectional elevation taken on line 5—5, Figure 6.

Figure 6 is a front elevation, partially in section taken on line 6—6, Figure 5.

Figure 7 is a perspective view of the grill plate elevator, the plate being shown in dotted lines.

Figure 8 is a detail showing a fragment of the elevator releasing pawl and the application of the push rod adapted to operate the same.

Figure 9 is a plan view of the scoring or marking device.

The device of this invention, as shown in the drawings, comprises a broiler, indicated in general by the reference character 10, and is provided with a rectangular body portion 10a, hav-

ing a flat top surface 12, and sides 14 and 16, the whole of which may rest upon legs or feet 18, or it may rest upon a suitable frame (not shown) without being provided with the legs 18.

The interior of the broiler 10 is provided with a suitable leverage, whereby a grill plate 20 upon which meat, etc., to be broiled, may be adjustably positioned with respect to a series of burners 22.

The plate 20 may also be withdrawn from the body of the broiler, for the purpose of placement or removal of meats, etc., and as shown in Figure 1 a drop-plate 24 to which the grill plate 20 is secured, provides not only an exterior finish to complete the frontal appearance of the device 10 when in normal closed position, but it also provides a means to withdraw the whole of the grill plate and the plate's entrained supporting mechanism, and at the same time affords means to manually vary the elevational position of the grill plate 20, all of which will be hereinafter more distinctly pointed out.

A scoring or pattern device 26 is adjustably positioned with respect to the grill plate 20, and is operable through a leverage system which is formed as follows.

The scoring device 26 comprises a frame having longitudinal and transversely extending members 29 and 30 which form a pattern, and are integrally joined to the frame 30'. The frame is provided with lugs 32, which extend through arcuately formed slots 31 in the side walls 14 and 16, when the scoring frame is in operative position. The lugs 32 are pivotally supported upon a rock-arm 34, which is oscillatable upon a boss 35 projecting from the sides 14 and 16. The rock-arm 34 is provided with an arcuately shaped dependent finger 36, the end of which is bifurcated for a purpose to be hereinafter set forth.

A link 37 connects the rock-arm 34 with a lever 38 which is substantially L shaped and which is secured upon a longitudinally extending square shaft 40, suitably journaled in the side-walls 14 and 16. The opposite end of the shaft 40 is fitted with a second lever 38a. The leg 38 of lever 38 is pivotally connected to a manually operated lever 42 having a handle 43, and which is provided with serrations or teeth 44 adapted to engage and interlock upon the lower lip of a slot 45 formed in the marginal front plate 46.

Springs 38b, have one end attached to the rock-arm 34, while the opposite ends thereof are attached to levers 38—38a, are adapted to counter-balance the dead-weight of the scoring frame 26.

The finger 36 which is formed as a part of rock-arm 34, is adapted to support a counterbalance and to forcibly lift the same. The balance 46 is pivoted upon a boss 47 and is provided with a weight 48, which is of slightly less weight than a swingable window 50 which is secured to the balance arm 46 by any suitable securing means 52. The balance arm 46 is provided with a bend 53, so that the arm, which is pivoted upon the exterior of the walls 14 and 16, may extend through an arcuate slot 54, and be attached to the window 50 at a point interior of the body 10a.

A manifold 55, shaped as an inverted "U", is adapted to supply fuel to each of a series of burners 22. Valves 56 are adapted to regulate the fuel supply. Superposed upon and resting as a hood over the burners 22, I provide refractory blocks 57, for the well known purpose of improving combustion of the fuel, as well as tending to regulate and make the dissipation of heat more even. As a further means of heat regulation to avoid spot temperatures in the grill plate 12, I place a sheet 58 of non-combustible material, such as asbestos, over the top surfaces of the refractory blocks 57.

The manifold 55 is provided with fuel from a chamber 60 which is built in the frame of the boiler, and it is upon the top surface of the longitudinally extending chamber 60, that I mount a pair of bearings 61 and 61a, while upon a second frame member 62, I place a second pair of corresponding bearings 63 and 63a. These bearings are adapted to receive fixed rods 64 for the purpose of slidably supporting mechanism 66 which in turn supports the grill plate 20 in adjustable relation to the burners 22 and which also permits the grill plate to be moved to a point exterior of the broiler. The bearings 61a and 63a are formed with an open side, as shown in Figures 6 and 7 to permit lateral expansion due to heat.

As shown in Figures 5, 6 and 7, the mechanism 66 comprises a pair of sleeves 68, which are integral, and are made rigid by means of a web 69, while rearwardly of the sleeves, I form vertically extending brackets 70, having bearings 71 to journal pintals 72, upon which is pivotally supported a frame 74, having arms 76.

The free ends of the arms 76 are pivotally secured to the rigid legs 78, which in turn are secured to the grill plate 20 by means of screws 80.

Counter-balances 70a are adapted to offset the weight of the assembled mechanism 66, and is formed of a tubular member 70b which is fitted over pintal 72 and rests between brackets 70. The member 70b is provided with rearwardly extending tongues 71b upon which weights 71c are slidably mounted to effect graduated and accurate balance, while a dependent member 71d, formed integrally with the member 71b, is adapted to bear against the frame 74 to lift upwardly thereagainst for the purpose aforeslated.

A brace 82 is pivotally secured to the lower end of the legs 78 and to the brackets 70 by means of pivots 84, and acts as an equalizer to keep the grill plate 20 in relatively level position when the plate is drawn forwardly as shown in Figure 5, however during the broiling period the grill plate 20 is tipped rearwardly so that grease and fat may drain by gravity therefrom. This tilting motion is obtained by reason of the fact that the spaces between pintal 72 and pivot

84, and between pivots 78a and 78b are of different magnitude, thereby causing leg 78 to be swung forwardly when the grill plate 20 is elevated to broiling position.

The legs 78 are formed with a web 86, which on its inner face is provided with a boss 88 to which a pawl 90 is pivotally supported, the free end of the pawl being adapted to engage one of a series of teeth formed in the web 69.

A push rod 94, adapted to be finger pressed, is journaled at its one end in handle 96, which is secured to the front drop plate 24, while the other end of the rod rests in an aperture 98 formed in web 86, and is adapted to press against the pawl 90 to lift it from engagement with the teeth 92, when it is desired to raise or lower the mechanism 66, as shown in Figures 5, 7, and 8. The pawl functions to support the plate 20 in any one of various elevated positions, and in so doing carries all of the unbalanced weight of the plate 20 and its associated train.

In order to heat the grill plate 20, for any purpose, burners 100, which are movable with the plate 20, are mounted upon bosses 102 formed as a part of the plate, and are supplied with fuel from a manifold 104, which is connected by means of a pipe 106 and flexible tube 108, with a valve 110 in connection with the chamber 60.

In order to bring the scoring device 26 into effective operation it is necessary that the device 26, conform with the position of the grill 20 regardless of whether it is tilted or in horizontal position, and to enable the device to be tilted, the levers 38 and 38a are provided with a slot 38' which is adapted to receive a pin 37 secured to the lower end of the links 37, thus permitting the frame and the link to assume any tilted position within reasonable limits, so that the frame may rest flat upon meats being broiled upon the grill 20.

To place the device of this invention in operation, it is only necessary to open valves 56 and to light the burners 22. After the broiler has come up to a sufficient heat, the grill plate 20 is manually pulled outwardly by means of handle 96 on drop plate 24. The articles to be broiled are then placed upon the plate 20, which is forced inwardly by sliding the whole of the lever mechanism 66 inwardly over rods 64.

The intensity of the heat applied to the article broiling may be varied, not only by means of the amount of fuel applied, but also by proximity of the article to the heat of the burners. And this is accomplished by lifting up upon the handle 96 and simultaneously pressing upon the finger rest 112 on push rod 94, to cause pawl 90 to be disengaged from teeth 92, and then lowering the whole of the adjustable mechanism 66, if the heat is too intense. If it is desired to more quickly broil the meat, it is only necessary to lift upwardly upon the handle 96 thereby causing the pawl 90 to follow and to move outwardly to a new position, which is then fixed by reason of the engagement of the pawl 90 with a new one of the teeth 92.

For the purpose of effect or appearance, it may be desirable to mark the steak being broiled, and to effect such searing marks, it is only necessary to lift handle 43 and to pull it outwardly, thereby lowering the scoring or marking device or frame 26, until it rests upon the steak, upon which the pattern of the frame is then seared.

The handle 43 and its associated parts should be operated for the purpose of lifting the swing-

able window 50 and the scoring device 26 prior to removal of any object being broiled. During the broiling operation the condition of the subject matter may be observed through the windows 5 116 which are preferably made of Pyrex glass or its equivalent.

In order to combine more general utility in the device of this invention, as previously mentioned, I have provided a grill plate 12 upon which 10 the so-called short-order may be prepared.

The plate 12 is hinged at 12a to the body 10a of the broiler, to provide ready access to the interior thereof for the purpose of inspection, cleaning or repair.

15 A groove 118 is adapted to catch grease, which drains through stub drain pipe 118a from which it enters detachable drain pipe 120. The pipe 120 being detachable for the purpose of removing hardened grease or fat derived from cooking 20 operations upon the grill 12.

It is obvious that various changes and modifications and variations may be made in practicing the invention in departure from the particular showing of the drawings and description 25 as given without, however, departing from the true spirit of the invention as defined by the scope of the appended claims.

I claim:

1. In a broiler having a movable grill plate, 30 means to apply heat in the area adjacent said plate and means to adjustably vary the position of said plate, said means comprising a pair of shafts, sleeves slidably mounted on said shafts, brackets on said sleeves, dependent legs on said 35 grill plate, arms joining said legs and said brackets, a pawl pivoted to a web joining said legs and capable of being adjustably positioned in teeth formed in fixed relation to said brackets, and finger pressed means to disengage said pawl 40 from said teeth, whereby said grill plate and its associated train may be moved in vertical directions and locked in selected position.

2. In a broiler having a movable grill plate, 45 means to apply heat in the areas adjacent the upper and under surfaces of said plate, said means comprising a plural number of burners, means to adjustably vary the position of said plate, said means comprising a pair of fixed shafts, sleeves slidably mounted on said shafts, brackets on said sleeves, dependent legs on said 50 grill plate, arms joining said legs and said brackets, a pawl pivoted in structure integral with said legs and capable of being adjustably positioned in teeth formed in fixed relation to 55 said sleeves, finger pressed means to disengage said pawl from said teeth, whereby said grill plate and its associated train may be moved in vertical directions and be locked in selected position, certain of said burners being in fixed 60 position and certain others of said burners being movable in conformity with movement of said grill plate.

3. In a broiler having an oven portion, in combination, a movable grill plate normally positioned within said oven, a fixed burner positioned over said grill plate when in said oven, a second burner, said second burner being permanently positioned adjacent the lower surface of said grill plate and being movable therewith, a base 65 formed of rods, a slideable grill plate support on said base whereby said grill plate and said second mentioned burner are movable inwardly and outwardly with respect to said oven, and means to vary the inclination of said grill plate from 70 zero inclination when in lowermost position to a

maximum inclination when raised to uppermost position, said means comprising substantially parallel arms of unequal length which are interposed between said base and said grill plate.

4. In a broiler having an oven portion, a movable grill plate normally positioned within said oven, a fixed burner positioned over said grill plate when in said oven, a second burner, said second burner being permanently positioned adjacent the lower surface of said grill plate and movable therewith, means whereby said grill and said second mentioned burner may be moved inwardly and outwardly with respect to said oven, said means comprising rods positioned in said oven, sleeves slidably positioned upon said rods, and arms interposed between said sleeves and said grill plate.

5. In a broiler having an oven portion, in combination, a movable grill plate adapted to be heated with burners adjacent the upper and lower surfaces thereof, one of said burners being stationary, the other of said burners being dependent upon and movable with said grill plate, a base, means whereby said grill plate and associated burner may be slidably moved upon said base in and out of said oven, arms, said arms being hingedly secured upon said base and connected to said grill plate whereby the same may be raised and lowered, a pawl to support said grill plate in a given position of elevation, finger pressed means to force disengagement of said pawl to lower said grill plate, said arms being of unequal length when in raised position to variably incline said grill plate from zero inclination when in lowermost position to a maximum inclination when raised to uppermost position.

6. In a broiler provided with an oven, an adjustably positionable grill plate, heating elements, one of said heating elements being adjacent the upper surface of said grill plate and in fixed position, the other of said heating elements being carried by said grill plate and in spaced relation to the underside thereof, a trackway to support said grill plate for horizontal movement in and out of said oven, links in substantially parallel relation and interposed between said trackway and said grill plate whereby said grill plate may be moved vertically with respect to said fixed heating element, a pawl gravitationally actuated to hold said grill plate in a given position of elevation, and finger pressed mechanically operated means to release said pawl to lower said grill plate with respect to said fixed heating element.

7. In a broiler having an oven provided with heating elements, a grill plate adjustably positionable within said oven, one of said heating elements being non-movable with respect to said grill plate, the other of said heating elements being supported upon said grill plate and being movable therewith, horizontal rods, sleeves slidably positioned on said rods, links interposed between said sleeves and said grill plate whereby the same may be swung through a range of elevational movement, said links being of unequal length whereby said grill plate may be progressively inclined from zero inclination when in lowermost position to a maximum inclination when in uppermost position whereby hot fats may be gravitationally drained therefrom, a pawl to support said grill plate in a given position of elevation, and finger pressed mechanical means to release said pawl to lower said grill plate.

8. In a broiler provided with an oven portion and having a grill plate adapted to be moved

- horizontally in and out of said oven, the combination of means to apply heat to said grill plate irrespective of its position relative to said oven, said means comprising a heating element mounted upon the under-side thereof and being movable therewith and having a source of energy connected with said heating element, said grill plate being provided with mechanical means to lift the same from a minimum to a maximum elevation, said lifting means being concurrently operable to progressively tilt said grill plate from zero inclination when in lowermost position to a maximum inclination when in uppermost position.
- 15 9. In a broiler provided with an oven portion and having a grill plate adapted to be slidably moved horizontally in and out of said oven, burners, one of said burners being fixedly positioned in said oven, the other of said burners being movable with said grill plate to apply heat thereto irrespective of the functional position of said grill plate, a base, linkage mounted upon said base and operatively connected with said

grill plate to permit selective variation of elevation thereof with respect to said fixed burner, said linkage being formed with member parts of unequal length when in lifted position whereby said grill plate will move from zero inclination when in lowermost position to a maximum inclination when in uppermost position.

10. In a broiler provided with an oven portion, rods secured in said oven, sleeves slidably positioned upon said rods, a grill plate, links interposed between said sleeves and said grill plate to support the same in variable positions of elevation, burners, one of said burners being in constant position, the other of said burners being movable with said grill plate to apply heat thereto irrespective of the functional position of said grill plate, manually operated means to vary the elevation of said grill plate, said links being of unequal length whereby said grill plate will move from zero inclination when in lowermost position to a maximum inclination when swung to uppermost position.

IRVIN H. RABER.
